UNITED STATES PATENT OFFICE

127,440

DESIGN FOR A CROCHETED BADGE

Nellie Barrow Jackson, New York, N. Y.

Application May 15, 1940, Serial No. 92,382

Term of patent 7 years

To all whom it may concern:

Be it known that I, Nellie Barrow Jackson, a citizen of the United States of America and residing in the city, county, and State of New York, have invented a new, original, and ornamental Design for a Crocheted Badge, of which the following is a specification, reference being had to the accompanying drawing, forming part thereof.

The figure is a plan view of a crocheted badge showing my new design.

I claim:

The ornamental design for a crocheted badge, as shown.

NELLIE BARROW JACKSON.
